UNITED STATES PATENT OFFICE

JOHN EMIL WILLIAM GREVE, OF CHEMNITZ, GERMANY, ASSIGNOR TO ASTRAWERKE AKTIENGESELLSCHAFT, OF CHEMNITZ, GERMANY

CALCULATING MACHINE

Application filed July 15, 1931, Serial No. 550,956, and in Austria May 23, 1931.

It is known to construct counting mechanisms with addition and subtraction actions as reversing gears, the counting wheels cooperating in pairs, and being adapted to be brought into operative relationship with driving means selectively, in such a way that the driven wheel is rotated in one direction and the other wheel in the opposite direction. The counting wheels are equipped with shifting cams for the carrying of tens, and these shifting cams act upon shifting noses on a tens carrying pawl. In the case of these counting mechanisms a separate shifting nose has hitherto been provided for each counting wheel, but this has the advantage that the shifting is effected more easily by one nose than by the other. The adjusting of such a counting mechanism is also rather complicated.

20 The invention consists in arranging a reversing gear, in which the tens shifting of both counting wheels is effected only from a single shifting nose of the tens carrying lever. In consequence of this arrangement, the tens carrying requires the same expenditure of power for both kinds of calculation, and furthermore, owing to the arrangement of the counting wheels as a whole, the driving members are shorter.

25 30 A counting mechanism according to the invention is illustrated in the accompanying drawing, in which

Figure 1 shows a counting mechanism with a rack drive, and

35 Figure 2 a counting mechanism with a sector drive.

On the type bars 1 of the machine, which are moved up and down in a known manner during one stroke of the machine, racks 2 are displaceably fitted in longitudinal slots 3 and 4, and are normally held in the position shown in Figure 1 by a spring 5. Counting wheels 6 and 7 are mounted upon their pivots 8 and 9 in a counting mechanism frame 10, which is rotatable about a shaft 11. A downwardly projecting arm 12 of the counting mechanism frame is provided with a slot 13, in which there engages a pin 14 which is riveted into a crank arm 15. The crank arm 15 is pinned to a rotatable shaft 16, which is ro-

tated through about 180° for the purpose of changing the counting mechanism over from addition to subtraction or conversely. This rotation may be effected in a known manner either by hand or during the operation of the machine. Obviously the counting wheels must be brought out of engagement with the driving members before being changed over. The counting wheels 6 and 7 have each a tens shifting cam, 17 and 18 respectively, which meshes with a nose 19 on the tens carrying lever 20.

The tens carrying levers 20 are rockably mounted upon a stationary shaft 21, and the lower end 22 of each is constructed as a pawl 65 with two steps, which cooperates with a ratchet lever 23, which is constantly pulled downwards by a spring 23'. It will be immediately obvious from the drawing that this ratchet lever is set free as soon as the 70 nose 19 of the tens carrying lever is pressed back, and that the driving rod 2 can then follow the pull of its spring 5, as a result of which the toothed wheel that is for the time being in mesh is rotated one division forward. In this manner the carrying of tens for example takes place in all the decimal places, if the counting mechanism contains a continuous series of nines and a number is added thereto in the units column. Otherwise the method of working of the parts described is as follows:—

When the type bar 1 is moved upwards, its lower end being rocked in such a manner that the racks 2 are out of engagement with the 85 toothed wheels, the spring 5 pulls the rack 2 into its lower position. During the down-stroke of the type bar, the rack 2 is brought into engagement with the toothed wheel, and this wheel is rotated a number of teeth that corresponds to the numeral inserted. Now when the toothed wheel is transferred from 9 to zero, the tens carrying nose 19 is pressed back by the shifting cam 17, and the ratchet lever 23 is pulled on to the lower notch of the pawl 22 by its spring 23', so that the rack of the next higher order is not held up by the ratchet lever 23 during its down stroke and the associated toothed wheel is thereby rotated one tooth further.

March 28, 1933.

CALCULATING MACHINE

Filed July 15, 1931

addition and one for subtraction, co-operating with one another upon several axes as a reversing gear, driving means for the counting wheels, means to bring either of the counting wheels into engagement with the driving means at will, a carrying cam on each of the counting wheels, and a single carrying nose upon the tens carrying lever adapted to be directly operated by the carrying cam on

5 10 whichever of the counting wheels is for the time being engaged by the driving means.

2. Counting mechanism for calculating and registering machines, comprising a movable frame, a pair of counting wheels mounted

15 20 upon several axes in said movable frame and co-operating with one another as a reversing gear, one wheel of each pair being for addition and the other for subtraction, driving means for the counting wheels, means for shifting the movable frame in such a way as to bring either of the counting wheels mounted therein into engagement with the driving means at will, a carrying cam on each of the counting wheels, and a single carrying nose

25 30 on the tens carrying lever adapted to be directly operated by the carrying cam on whichever of the counting wheels is for the time being engaged by the driving means.

In testimony whereof I have signed my name to this specification.

JOHN EMIL WILLIAM GREVE.
